Primary Examiner — Alison M Oftstun(74) *Attorney, Agent, or Firm* — Quarles & Brady LLP;
James J. Aquilina(57) **CLAIM**

The ornamental design for a blade as shown and described.

DESCRIPTION

FIG. 1 is a front, top, left side perspective view of a blade, in accordance with the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures illustrate portions of the blade and form no part of the claimed design.

1 Claim, 7 Drawing Sheets(56)
